UNITED STATES PATENT OFFICE.

EDWIN M. ROSENBLUTH, OF PHILADELPHIA, PENNSYLVANIA.

CARRIAGE-LAMP.

SPECIFICATION forming part of Letters Patent No. 693,070, dated February 11, 1902.

Application filed May 14, 1901. Serial No. 60,140. (No model.)

To all whom it may concern:

Be it known that I, EDWIN M. ROSENBLUTH, of Philadelphia, in the State of Pennsylvania, have invented certain new and useful Improvements in Carriage-Lamps, whereof the following is a specification, reference being had to the accompanying drawings.

My invention relates to carriage-lamps arranged to burn oil within an inclosed flame-chamber provided with means to draft a supply of air from the exterior of said chamber to supply the burner.

It is the object of my invention to provide a lamp of the class specified comprising a magazine arranged to contain an ample supply of free oil and an automatic capillary regulator, whereby the supply of oil delivered from the magazine to the burner shall be uniformly maintained as required for the maximum efficiency of the lamp regardless of the vibration to which the lamp is subjected when attached to a vehicle.

It is a further object of my invention to so construct and arrange such a lamp that the operator may readily ascertain the quantity of oil available in the magazine at any given instant.

My invention consists in the novel features of construction and arrangement hereinafter more definitely specified and claimed.

In the accompanying drawings, Figure 1 is a vertical sectional view of a carriage-lamp conveniently embodying my invention. Fig. 2 is a side elevation of the oil-magazine and capillary regulator of said lamp, said magazine being partially sectioned to show the relation of the regulator thereto.

Referring to Fig. 1, A is the inclosed flame-chamber, whose floor A' is provided with an upwardly-projecting air-draft dome B, having an air-outlet b at its top. The bottom of said dome B opens into the air-draft chamber A² within the annular flange A³, depending from the floor of the flame-chamber. Said flange A³ is provided with air-inlet apertures a², so arranged as to admit the proper supply of air to the flame-chamber A through the draft-chamber A² and dome B. The products of combustion, &c., escape from said flame-chamber through the chimney A⁴ at the top thereof. The wall A⁵ of the flame-chamber A is provided with a socket a⁵, whereby

the lamp may be supported upon a suitable bracket attached to a carriage. I find it convenient to provide the flame-chamber A with a front lens or panel of glass A⁶ and a reflector A⁷, adjoining the rear wall A⁸, which reflector is apertured at a⁷ to permit the transmission of light through the rear signal-jewel a⁸. However, the precise details of construction of the flame-chamber are not of the essence of my invention, which relates more particularly to the combination of the burner and oil-magazine with an intermediate screen, which latter is in such capillary communication with the burner-wick and with the free oil in said magazine as to render the delivery of the oil from the magazine to the burner uniform regardless of the vibration of the lamp when attached to a vehicle.

Within the draft-dome B is mounted the burner C, whose wick-tube c projects through the air-outlet b at the top of said dome. The regulator-casing D is removably secured to said burner C conveniently by the screw-thread d, and said casing comprises a laterally-extending circumferential flange d', arranged to abut against the lower edge of the flange A³ to limit the upward extension of the burner C with respect to the flame-chamber A. Within said casing D is concentrically mounted a cylindrical partition D', which depends through the bottom flange d³ of the casing, to which it is soldered, and serves to support a screen of absorbent material D², conveniently formed of a tube of wicking in which is embedded a mass of absorbent material d², such as cotton fibers or the like, through which the oil is transmitted by capillary attraction to the burner-wick C'.

The oil-magazine F comprises a screw-threaded neck f, fitted to the screw-threaded flange A³, and the internal flange F' upon the magazine is provided with a gasket f', arranged to impinge upon the bottom flange d³ of the casing D and to make an oil-tight joint therewith. As shown, said flange F' and gasket f' incline downwardly toward the center of the magazine, so as to discharge within the latter any oil which may accidentally be deposited upon them.

The parts above described being assembled as shown in Fig. 1, the oil-magazine is in capillary communication through the screen D²

with the wick C', so that regardless of the vibration of the lamp when attached to a vehicle the wick C' cannot be overcharged with oil, the oil delivered to it being comminuted by its passage through said screen. Moreover, although said wick C' is in capillary communication with the screen D² it is capable of adjustment independently thereof through the burner C by means of the wick-shaft C².

The operator may ascertain the quantity of free oil available in the magazine at any instant by partially withdrawing the regulator-casing D from the magazine F, as shown in Fig. 2, the depending portion of the cylinder D' being obliquely terminated, as shown, to afford the maximum view of the interior of the magazine. Such an arrangement is also advantageous in that all of the oil dripped from said cylinder D' is confined to the magazine F. The rod F², fixed in the magazine F, indicates the depth to which the latter should be filled with oil and being resilient is not liable to be broken.

The tube of absorbent textile material comprising the screen D² is conveniently fixed within the cylinder D' by stitches, as indicated at d⁴, so that said screen forms a floor to retain the absorbent material d² and wick C'.

The lamp shown in Fig. 1 is arranged to be suspended, as aforesaid, by means of the socket a³, indicated thereon, however, the oil-magazine and capillary regulator being removable, as above described. For convenience of manipulation of said magazine I secure upon the bottom thereof a tubular extension F³, which serves both as a handle and as a supporting-standard. Said standard serves as a waterproof shelter for the match-box F⁴, whose basal flange F⁵ extends from said standard, as shown in section in Fig. 1, and serves as a pedestal for the oil-magazine F when in the position shown in Fig. 2. Said match-box F⁴ being provided with a detent-spring f⁴, which normally projects through the aperture f³ in the standard, may be released and removed from the latter at the will of the operator by forcing said spring inwardly and withdrawing said box by its basal flange. There being a definite position of the burner C with respect to the draft-dome B, in which the maximum efficiency of the burner is secured, I find it desirable to so construct the regulator-casing D that the distance between its abutment-flange d' and the top of the burner C may be adjustably varied in the primary assembling of the parts in correspondence with the slight variations in relative position of the dome B and the depending flange A³, unavoidable in the manual assembling of the latter, and therefore I construct said casing D of two sections telescopically fitted, as shown in Fig. 1, which sections are first adjusted in proper relation within the assembled dome B and flange A³ and subsequently seamed or soldered together at d⁵.

Although I have found it convenient to form the cylinder D' of a cut section of perforated metal, as shown in Figs. 1 and 2, it is to be understood that it may be formed of other material. On the other hand, my improvements above described are advantageous in that whereas the free oil is screened from the burner-wick, and thus prevented from splashing through the wick-tube, only a minute quantity of the oil is suspended in the absorbent material of the screen, the bulk of the supply of oil being free and visible within the magazine, so that the precise quantity thereof available may be ascertained at any instant. Moreover, the bulk of the absorbent material being reduced to the minimum, a corresponding increase in the oil capacity of the lamp is secured. For instance, a magazine of the size shown when filled with saturated absorbent material would contain a supply sufficient for approximately ten hours, whereas with the improved form constituting my invention an oil-supply for fifty-hours' service of the lamp may be carried.

I do not desire to limit myself to the precise construction herein set forth, as it is obvious that various modifications may be made therein without departing from the essential features of my invention.

I claim—

1. In a lamp, the combination with an enclosed flame-chamber; of a draft-dome projecting within said chamber from the floor thereof; a burner surrounded by, and projecting through the top of said dome; means to admit a draft of air to said dome; a regulator-casing secured to said burner in removable relation with said flame-chamber; a wick depending from said burner, and terminating within said regulator-casing; a second wick extending below said casing, and terminating within the latter, in capillary communication with the first wick aforesaid; and an oil-magazine removably secured to said flame-chamber, and arranged to maintain said regulator-casing in operative position, substantially as set forth.

2. In a lamp, the combination with a burner; of a capillary-regulator casing attached to said burner; a screen-cylinder fixed within said casing, and depending below the bottom thereof; a wick depending from said burner within said screen-cylinder; a screen of absorbent material fixed in said screen-cylinder, in capillary communication with said wick; and an oil-magazine removably secured to said casing, in capillary communication with said screen, substantially as set forth.

3. In a lamp, the combination with a burner; of a capillary-regulator casing attached to said burner; a screen-cylinder fixed within said casing, and depending below the bottom thereof; a wick depending from said burner within said screen-cylinder; a screen of absorbent material fixed in said screen-cylinder, in capillary communication with said wick; means to adjust said wick through said

burner, independently of said screen; a flange upon the bottom of said casing, exterior to said screen-cylinder; an oil-magazine provided with a gasket of resilient material; and means to seal the bottom flange of said casing upon said gasket, with said oil-magazine in capillary communication with said screen, substantially as set forth.

4. In a lamp, the combination with an ¹⁰ closed flame-chamber; of an annular flange depending from the floor of said flame-chamber; a screw-thread upon said flange; a burner surrounded by said flange and projecting within said flame-chamber; a regulator-casing ¹⁵ removably secured to said burner; a screen-cylinder fixed within said casing, in concentric relation therewith; a wick depending from said burner within said screen-cylinder; a screen of absorbent material fixed ²⁰ in said cylinder, in capillary communication with said wick; a circumferential flange extending laterally from said casing, and abutting against said depending annular flange; a flange upon the bottom of said casing, exterior to said screen-cylinder; an oil-magazine ²⁵ having a screw-threaded neck; a flange within said neck; and a gasket upon said flange opposed to the bottom flange upon said casing, substantially as set forth.

5. In a lamp of the class described; the combination with a burner; of a capillary regulator consisting of an upper casing-section secured to said burner; a lower casing-section telescopically fitted to said upper section; a screen of absorbent material; means to fix said screen in said lower section; and a wick depending from said burner in capillary communication with said screen, substantially as set forth.

6. In a lamp, the combination with a burner; of a capillary-regulator casing attached to said burner; a screen-cylinder fixed within said casing, and obliquely elongated below the bottom thereof; a wick depending from said burner within said screen-cylinder; a screen of absorbent material fixed in said screen-cylinder in capillary communication with said wick; and an oil-magazine removably secured to said casing in capillary communication with said screen, substantially as set forth.

7. In a lamp, the combination with a burner; of a capillary-regulator casing attached to said burner; a screen-cylinder fixed within said casing and obliquely elongated below the bottom thereof; a wick depending from said burner within said screen-cylinder; a screen comprising a tube of absorbent textile mate-

rial arranged to form a floor in said cylinder in capillary communication with said wick; ⁶⁰ means to secure said absorbent tube below the bottom of said casing upon the elongated side of said screen-cylinder; and an oil-magazine removably secured to said casing in capillary communication with said screen ⁶⁵ through said extension thereof, substantially as set forth.

8. In a lamp, the combination with a burner; of a capillary-regulator casing attached to said burner; a screen-cylinder formed of perforated sheet metal fixed within said casing and depending below the bottom thereof; a wick depending from said burner within said screen-cylinder; a screen of absorbent material fixed in said screen-cylinder in capillary communication with said wick; and an oil-magazine removably secured to said casing in capillary communication with said screen, substantially as set forth.

9. In a lamp, the combination with a burner; of a capillary-regulator casing attached to said burner; a screen-cylinder fixed within said casing; a wick depending from said burner within said screen-cylinder; a screen of absorbent material fixed in said screen-cylinder ⁸⁵ in capillary communication with said wick; a flange upon the bottom of said casing exterior to said screen-cylinder; an oil-magazine provided with an opening in its top; an annular flange within said opening inclined ⁹⁰ downwardly toward the center of said oil-magazine; a gasket fitted upon said annular flange and similarly inclined; and means to seal the bottom flange of said casing upon said gasket, with said oil-magazine in capillary communication with said screen, substantially as set forth.

10. In a lamp, the combination with a burner; of a wick depending therefrom; a capillary-regulator casing attached to said ¹⁰⁰ burner and surrounding said wick; a perforated screen-cylinder fixed within said casing; a screen of absorbent textile material stitched to said screen-cylinder and forming a floor therein in capillary communication with said ¹⁰⁵ wick; and an oil-magazine in capillary communication with said screen, substantially as set forth.

In testimony whereof I have hereunto signed my name at Philadelphia, Pennsylvania, this 9th day of May, 1901.

EDWIN M. ROSENBLUTH.
